CLAIM

The ornamental design for a hose protection device, as shown and described.

DESCRIPTION

FIG. 1 is a perspective view of a hose protection device showing my new design;

FIG. 2 is a front view, the back view, top view, and bottom view being a mirror image thereof; and,

FIG. 3 is a left side view, the right side view being a mirror image thereof.

In the drawings, the broken lines showing a ground anchor illustrate environment and form no part of the claimed design.
